UNITED STATES PATENT OFFICE.

JULIUS H. G. WOLF, OF SAN FRANCISCO, CALIFORNIA.

COMPOSITE RAILWAY CROSS-TIE.

No. 828,991.

Specification of Letters Patent.

Patented Aug. 21, 1908.

Application filed February 10, 1904. Serial No. 193,024.

To all whom it may concern:

Be it known that I, JULIUS HERMAN GEORGE WOLF, a citizen of the United States, residing at San Francisco, State of California, have invented a new, useful, and Improved Composite Railway Cross-Tie for either Street or Steam Railway Purposes, of which the following is a specification, reference being had to the accompanying drawings.

10 This invention relates to an improvement in the making of composite railway cross-ties.

The object sought is to present a composite cross-tie which in serving its functions as 15 a tie shall possess every advantage of the wooden tie now in use and add thereto those qualities or requisites which wooden ties lack.

The strength of a wooden tie lies in the strength of its fibers, which are subject to 20 decay. The strength of the composite tie rests in practically indestructible materials.

A practical embodiment of the invention is represented in the accompanying drawings, forming a part of this specification, in which 25 similar characters of reference indicate corresponding parts in all the views.

Figure 1 is a top plan view of the tie, the left-hand portion of it being shown complete with the rail upon it and showing on the right 30 side of the medial line X Y the same view without the rail. A portion of the open metallic reinforcement is omitted to more clearly show details under the rail-seat. Fig. 2 is a longitudinal sectional elevation of the 35 tie, taken through one of the spike-bolts, showing the method of holding the rail to the tie and showing the open metallic reinforcement, portions of which are omitted to enhance the clearness of the drawings. Fig. 3 40 is a cross-sectional elevation through one of the same bolts, showing the method of rail attachment and showing the open metallic reinforcement placed within and passing through the encircling straps to which the 45 spike-bolts are attached. Fig. 4 is a drawing of one type of open metallic reinforcement known in the trade as "expanded" metal, and Fig. 5 is another type of the same reinforcement and known as "wire-cloth."

50 In carrying out this invention there is employed a body of concrete or artificial stone A, in which is embedded an open metallic reinforcement B. This "open" metallic reinforcement may be either expanded metal, 55 wire lath, heavy wire-cloth, or any metallic substance of similar character which serves

the purposes of these materials in reinforcing concrete. This open metallic reinforcement is placed trough-shaped, enveloping the concrete on the bottom and the sides, as clearly 60 shown in Fig. 3. The sheet of metal is to be in one continuous piece with the sides or webs formed by bending the edges upward, as indicated by B in Fig. 3. In this manner it will protect the concrete from disruption 65 when impact strains are brought upon it, the web or side members taking the cross bending strains, while the bottom portion will assist in preserving the integrity of the entire mass. The concrete may be cut away on the 70 bottom, as shown in Fig. 2, so as to prevent "center-binding" of the tie and also to reduce its weight.

It will be observed that the metallic reinforcement is entirely independent of the attaching device for holding the rails to the tie. It consists simply of two enveloping straps C C under each rail, completely surrounding the concrete of the tie and sitting flush with the faces of the tie on sides, top, and bottom. 80 Within these straps will pass the trough-shaped metallic reinforcement. Hence the strain upon the medium for holding the rails upon the tie is carried by the body of the tie and not by any particular portion of the mass 85 which might crack or disintegrate it.

The enveloping straps are pierced by slotted holes, one hole to each strap, on the top surface, as shown in the plan view, Fig. 1. Through each hole is a short bolt D, termed a 90 "spike-bolt," made with a head in the shape of spike, as is now used to hold down rails with the ordinary wooden tie. The nut E (shown in Figs. 2 and 3) engages the threads of the bolts and screws up tightly against the 95 under side of the strap. This fact permits any desired amount of strain to be brought upon the bolt and insures the flange of the rail being held fast at all times. In order that an offset wrench may be used to screw 100 up the nut, the concrete is cut away in a dish-shaped manner, as indicated by G and shown in the three views. In Fig. 3 the bottom of this recess is shown to pitch outward, so as to insure drainage and not to form a closed 105 pocket.

While the above constitutes what is considered the preferred form of this invention, slight modifications, variations, and alterations of structural details may be resorted 110 to without violating the principles of the design for this tie, and the right is reserved to

make slight changes within the scope of the invention as practice may show to be desired. The purposes and intent of the invention are set forth in the following claims.

5. The phrase "trough-shaped" in the claims is to be understood as including any trough-shaped metallic reinforcement either open at the top or closed at the top or inverted.

My invention is not limited to the mechanism here shown for securing the rails to the tie, as other modes of accomplishing this result might be used—as, for instance, by substituting two blocks of wood of very nearly the same vertical depth as the thickness of 15 the tie for the two enveloping straps at each end of the tie, so that the ordinary spike now in use with timber ties could be used for attaching the rails instead of using the spike-bolt.

20. What I claim as new, and desire to secure by Letters Patent, is—

1. A railway cross-tie comprising a body of concrete or artificial stone, with vertical sheets of open metallic reinforcement embedded longitudinally therein, said sheets being of less width or vertical dimension in the middle portion than under the rails to give elasticity to the tie, and having the concrete cut away in the middle portion to prevent 25 the tie from becoming center-bound by the packing of ballast around it, substantially as described.

2. A railway cross-tie comprising a body of concrete or artificial stone, a metallic band 30 around said body adjacent to each rail, and means for securing the rail to the band, substantially as described.

3. A railway cross-tie comprising a body of concrete or artificial stone with open metallic reinforcement embedded longitudinally 40 therein, a metallic band around said body adjacent to each rail, and means for securing the rail to the band independently of said reinforcement, substantially as described.

45. 4. A railway cross-tie comprising a body of concrete or artificial stone with a trough-shaped sheet of laterally-expanded metallic reinforcement longitudinally embedded therein, substantially as described.

50. 5. A railway cross-tie comprising a body of concrete or artificial stone with a trough-shaped sheet of open metallic reinforcement longitudinally embedded therein, the sides of the trough being of greater vertical dimensions under the rails than the middle portion, substantially as described.

55. 6. A railway cross-tie comprising a body of concrete or artificial stone with laterally-expanded metallic reinforcement embedded

longitudinally therein having two vertical 60 members and a horizontal member, substantially as described.

7. A railway cross-tie comprising a body of concrete or artificial stone with laterally-expanded metallic reinforcement embedded 65 longitudinally therein having a vertical member and a horizontal member in a single sheet, substantially as described.

8. A railway cross-tie, comprising a body of concrete, or artificial stone, with a sheet of 70 open metallic reinforcement embedded therein, said sheet of reinforcement being trough-shaped, having a horizontal bottom portion and with raised sides, the tie being of greater vertical dimensions under the rails than in 75 the middle portion, as set forth.

9. A railway cross-tie, comprising a body of concrete, or artificial stone, a sheet of open metallic reinforcement embedded therein, and two enveloping straps under each rail for 80 the purpose, with the assistance of spike-bolts, of attaching the rails to the tie, said enveloping straps being of metal and going completely around the tie, on its four sides, as set forth.

85. 10. A railway cross-tie comprising a body of concrete, or artificial stone, a sheet of open metallic reinforcement embedded therein, enveloping straps of metal under each rail, and spike-bolts passing through slotted holes 90 of the enveloping straps in order to bolt, with the assistance of nuts, the rail to the tie, as set forth.

11. A railway cross-tie comprising a body of concrete, or artificial stone, a sheet of open 95 metallic reinforcement embedded therein, enveloping straps of metal under each rail, spike-bolts to pierce said straps, and a recess in the concrete under each nut in order that an offset wrench may be inserted under the 100 strap to engage the nut for the purpose of screwing it up.

12. A metal tension member for combined 105 metal and concrete railroad-tie construction, comprising a longitudinal portion and a portion of the same expanded laterally.

13. In a combined concrete and metal tie, the combination of a concrete body, a metal member extending longitudinally of the same and having extending latticed projections in 110 the form of "expanded metal."

In witness whereof I have hereunto set my hand in the presence of two subscribing witnesses.
